CLAIM

I claim the ornamental design for an input pen with ball-point pen, as shown and described.

DESCRIPTION

FIG. 1 is a perspective view of an input pen with ball-point pen.

FIG. 2 is a front elevational view thereof.

FIG. 3 is a rear elevational view thereof.

FIG. 4 is a side elevational view, the opposite side being a mirror image thereof;

FIG. 5 is a front elevational view with the cap member in a stored position and the ball-point pen tip exposed;

FIG. 6 is a bottom plan view; and,

FIG. 7 is a top plan view thereof.
